UNITED STATES PATENT OFFICE.

HENRY ESCH, JR., OF MANITOWOC, WISCONSIN.

DESIGN FOR A COMBINED COLLAR-BUTTON AND TIE-SLIDE OR SIMILAR ARTICLE.

55,761.

Specification for Design.

Patented July 13, 1920.

Application filed April 19, 1920. Serial No. 375,176. Term of patent 14 years.

To all whom it may concern:

Be it known that I, HENRY ESCH, Jr., a citizen of the United States, and residing in the city of Manitowoc, county of Manitowoc, and State of Wisconsin, have invented a new, original, and ornamental Design for a Combined Collar-Button and Tie-Slide or Similar Article, of which the following is the specification, reference being had to the accompanying drawings, forming a part thereof.

In the drawings:

Figure 1 is a top plan view of a combined

collar button and tie slide, illustrating the design of my invention.

Fig. 2 is a bottom plan view thereof.

Fig. 3 is an end view thereof in elevation.

I claim:

The ornamental design for a combined collar button and tie slide or similar article as shown.

HENRY ESCH, JR.
